CORDLESS ELECTRIC LAWN MOWER

John W. Graham and Russell A. Fritts, Phoenix, Roderick F. Bunyea, Towson, Michael P. Ballone, Baltimore, and Ronald B. Kemnitzer, Towson, Md., and Stefan A. Unger, Chicago, Ill., assignors to The Black and Decker Manufacturing Company, Towson, Md., a corporation of Maryland

Filed Sept. 17, 1969, Ser. No. 19,178

Term of patent 14 years

Int. Cl. D8—01

U.S. Cl. D40—1

FIG. 1

FIG. 2

FIG. 3

FIG. 5

FIG. 1 is a perspective view of a cordless electric lawn mower of our design;

FIG. 2 is an enlarged side elevational view of the lawn mower of FIG. 1;

FIG. 3 is an enlarged front elevational view of the lawn mower of FIG. 1;

FIG. 4 is an enlarged top plan view of the lawn mower of FIG. 1; and

FIG. 5 is an enlarged rear elevational view of the lawn mower of FIG. 1.

The handle has been shown broken away for ease of illustration in FIGS. 2-5.

We claim:

The ornamental design for a cordless electric lawn mower, as shown and described.
